UNITED STATES PATENT OFFICE.

HENRY W. FISHEL, OF NEW YORK, N. Y., ASSIGNOR TO HENRY W. FISHEL AND THEODORE H. FISHEL, OF NEW YORK, N. Y., COPARTNERS TRADING AS FISHEL, NESSLER & COMPANY.

DESIGN FOR A JEWELRY ORNAMENT.

40,988.

Specification for Design.

Patented Nov. 15, 1910.

Application filed September 14, 1910. Serial No. 582,107. Term of patent 7 years.

To all whom it may concern:

Be it known that I, HENRY W. FISHEL, a citizen of the United States, residing at the borough of Manhattan, city of New York, in the county of New York and State of New York, have invented a certain new, original, and ornamental Design for a Jewelry Ornament, of which the following is a specification, reference being had therein to the accompanying drawings, forming part thereof.

Figure 1 is a front elevation of a jewelry ornament showing my design. Fig. 2 is an end or edge elevation of the same.

I claim:

The ornamental design for a jewelry ornament as shown.

In testimony whereof I have affixed my signature in presence of two witnesses.

HENRY W. FISHEL.

Witnesses:

BERNARD COWEN,
HARRY LEWIS.
